UNITED STATES PATENT OFFICE.

WALTER A. SHEAFFER, OF FORT MADISON, IOWA.

DESIGN FOR A PENCIL.

59,035.

Specification for Design. Patented Sept. 13, 1921.

Application filed April 10, 1919. Serial No. 289,143. Term of patent 14 years.

To all whom it may concern:

Be it known that I, WALTER A. SHEAFFER, a citizen of the United States, residing at Fort Madison, in the county of Lee and State of Iowa, have invented a new, original, and ornamental Design for a Pencil, of which the following is a specification, reference being had to the accompanying drawing, forming a part thereof, and wherein—

The figure is a view in perspective of the pencil illustrating my new design.

I claim:

The ornamental design for a pencil, as shown.

San Francisco, Cal., April 2nd, 1919.

WALTER A. SHEAFFER.
